(57) **ABSTRACT**

A locking assembly for releasably-locking a lid to a container includes shaped portions disposed on the lid and container that are configured to allow slidable engagement of the lid relative to the container along a movement axis. A locking nub disposed on a wall of the container and a nub receiving portion disposed on the lid are engaged when the lid and container are slidably engaged together, which restricts sliding movement of the lid relative to the container along the movement axis. The wall of the container is inwardly compressible to move the locking nub outwardly of the nub receiving portion, which allows slidable movement relative to the container along the movement axis.

**CROSS-REFERENCE TO RELATED
APPLICATION(S)**

This patent application is a continuation of and claims the benefit of priority to U.S. application Ser. No. 17/661,566, filed May 2, 2022, which is a continuation of U.S. application Ser. No. 17/263,877, filed Jan. 27, 2021, which is the U.S. national phase entry under 35 U.S.C. § 371 of International Application No. PCT/CN2019/071708, filed on Jan. 15, 2019, which claims the benefit of priority from Hong Kong Application No. 18109773.4, filed on Jul. 27, 2018, the entireties of each of which are incorporated herein by reference.

TECHNICAL FIELD

The present invention relates to a locking mechanisms for containers including for instance child-safe locks.

BACKGROUND OF THE INVENTION

Certain food products, cleaning agents, medications and the like that are commonly found in the home may be dangerous to young children. Such substances must be transported and stored in containers having “child-safe” locking mechanisms for locking the lid of the container and which are difficult for children to open by means of challenging their cognition, dexterity and/or strength. Currently, existing child-safe locking mechanisms tend to utilise variations on one of a few common designs, such as the “push and twist” style cap. Whilst oftentimes effective, the prevalent use of this style of cap lock has become so widely used that children, of even younger ages, have become accustomed to them thus limiting their potential long-term effectiveness.

SUMMARY OF THE INVENTION

The present invention seeks to alleviate at least one of the above-described problems.

The present invention may involve several broad forms. Embodiments of the present invention may include one or any combination of the different broad forms herein described.

In a first broad form, the present invention provides a locking assembly for releasably-locking a lid to a container so that the lid covers an opening of the container, the locking assembly including: shaped portions disposed on the lid and container that are configured to allow slidable engagement of the lid relative to the container along a movement axis between a first configuration in which the lid covers the opening in to a second configuration in which the lid does not cover the opening; a locking nub disposed on a wall of the container; a nub receiving portion disposed on the lid; and wherein when the lid and container are slidably engaged together in the first configuration, the locking nub disposed on the container is received within the nub receiving portion disposed on the lid so as to restrict sliding movement of the lid relative to the container along the movement axis from the first configuration in to the second configuration, and, wherein the wall of the container is inwardly depressible so as to move the locking nub outwardly of the nub receiving portion whereby the lid is then able to be slidably moved

2

relative to the container along the movement axis from the first configuration in to the second configuration.

Preferably, at least one of the shaped portions may form a pair of rails disposed along a rim of the container opening, and at least one of the shaped portions form rail engagement elements disposed on the lid that are configured for slidable engagement with the rails.

Preferably, the locking nubs may extend outwardly from opposing elongate sidewalls of the container along at least one axis that is transverse to the movement axis.

Preferably, the lid may include a main body configured for covering the opening of the container, and side portions extending perpendicularly from elongate side-edges of the main body.

Preferably, the side portions may each include a nub receiving portion for receiving one of the locking nubs when the lid is slidably engaged with the container in the first configuration.

Preferably, the nub receiving portion may include at least one of a slot, a recess and a rebate.

Preferably, the present invention may include a humidity control material disposed on the lid of the container.

Preferably, the container may be formed from at least one of a tin, aluminium or polymeric material.

In another broad form, the present invention provides a locking assembly for releasably-locking a lid to a container so that the lid covers an opening of the container, the locking assembly including: shaped portions disposed on the lid and container that are configured to allow slidable engagement of the lid relative to the container along a movement axis between a first configuration in which the lid covers the opening in to a second configuration in which the lid does not cover the opening; a locking nub disposed on the lid; a nub receiving portion disposed on a wall of the container; and wherein when the lid and container are slidably engaged together in the first configuration, the locking nub disposed on the lid is received within the nub receiving portion disposed on the container so as to restrict sliding movement of the lid relative to the container along the movement axis from the first configuration in to the second configuration, and, wherein the wall of the container is inwardly depressible so that the locking nub is moved relatively outwardly of the nub receiving portion and whereby the lid is then able to be slidably moved relative to the container along the movement axis from the first configuration in to the second configuration.

BRIEF DESCRIPTION OF THE DRAWINGS

The present invention will become more fully understood from the following detailed description of a preferred but non-limiting embodiments thereof, described in connection with the accompanying drawings, wherein:

FIG. 1A shows a perspective view of a container having an opening covered by a lid in accordance with a first embodiment;

FIG. 1B shows a perspective view of the container having an opening partially covered by a lid in accordance with the first embodiment;

FIG. 2 shows a side-view of the container having the opening covered by the lid in accordance with the first embodiment;

FIG. 3 shows a front-view of the container having the opening covered by the lid in accordance with the first embodiment; and

FIG. 4 shows a bottom-view of the container having the opening covered by the lid in accordance with the first embodiment;

DETAILED DESCRIPTION OF THE PREFERRED EMBODIMENTS

Preferred embodiments of the present invention will now be described herein with reference to FIGS. 1 to 4. The embodiments comprise a container (10A, 10B, 10C) having a child-safe type locking mechanism for releasably locking a lid (20A) on to the container (10A, 10B, 10C) so that the lid (20A, 20B, 20C) covers an opening of the container (10A, 10B, 10C).

The locking assembly includes shaped portions disposed on the lid (20A, 20B, 20C) and on the container (10A, 10B, 10C) that are configured to allow slidable engagement of the lid (20A, 20B, 20C) relative to the container (10A, 10B, 10C) along a movement axis (X) between a first configuration (as shown in FIG. 1A) in which the lid covers the opening in to a second configuration (as shown in FIG. 1B) in which the lid does not cover the opening;

In this embodiment the container is substantially rectangular-shaped and includes side walls (10B, 10C). Shaped portions in the form of a pair of parallel rails (10D, 10E) are disposed along a rim of the container opening on the side walls (10B, 10C) of the container (10A, 10B, 10C). Shaped portions in the form of rail engagement elements (20B, 20C) are also disposed on the lid (20A, 20B, 20C) and are configured for slidable engagement with the parallel rails (10D, 10E).

The lid (20A, 20B, 20C) includes a main body (20A) comprises a substantially flat rectangular portion (20A) that is configured for covering the opening of the container. and side portions (20B, 20C) that extend substantially perpendicularly from elongate side-edges of the main body (20A).

The locking assembly comprises locking nubs (10B', 10a) protruding outwardly from each of the side-walls (10B, 10C) of the container along an axis (Y) which is transverse to the movement axis (X), and, locking nub receiving portions in the form of slots (20B', 20C') that are cut out of each of the side portions (20B, 20C) of the lid. The slots (20B', 20C') are shaped and dimensioned for snugly receiving their corresponding locking nubs. When the lid (20A, 20B, 20C) and container (10A, 10B, 10C) are slidably engaged together in the first configuration, the locking nubs (10B', 10a) disposed on the container (10A, 10B, 10C) are received within the corresponding slots (20B', 20C') disposed on the lid (20A, 20B, 20C) so as to restrict sliding movement of the lid (20A, 20B, 20C) relative to the container along the movement axis (X) from the first configuration in to the second configuration. The wall of the container (which in this embodiment is made from tin or aluminium) is configured to be inwardly compressible by a user so as to cause movement of the locking nubs (10B', 10C') outwardly of the slots (20B', 20C') whereby the lid (20A, 20B, 20C) is then able to be slidably moved relative to the container (10A, 10B, 10C) along the movement axis (X) from the first configuration in to the second configuration.

In certain embodiments, the locking nubs may be disposed on the lid whilst the locking nub receiving portions may be disposed on the container in reverse fashion.

In yet further embodiments, the container may include a humidity control material. For instance such a material may be disposed on the lid of the container so as to face inwardly of the container when the lid covers the container and to control or regulate humidity within the container during use.

It would be appreciated that embodiments of the present invention as described herein require a degree of cognitive and dexterity ability to open the container which is designed to exceed the ability of young children. Further, such a solution provides added variability to its use that extends in contrast to existing methodologies for effecting child-safe locking mechanisms. Yet further, the streamlined design and relatively simplified function allows it to be applied to a wide variety of container, jars and bottles in numerous materials and sizes. Yet further, embodiments of the present invention are advantageous in that the combined lid/locking collar assembly may be pressed down in to secured engagement with the container when the combined lid/locking collar assembly is arranged in any position of coaxial rotation relative to the container thus making it easier to operate and saving time for the user.

Those skilled in the art will appreciate that the invention described herein is susceptible to variations and modifications other than those specifically described without departing from the scope of the invention. All such variations and modification which become apparent to persons skilled in the art, should be considered to fall within the spirit and scope of the invention as broadly hereinbefore described. It is to be understood that the invention includes all such variations and modifications. The invention also includes all of the steps and features, referred or indicated in the specification, individually or collectively, and any and all combinations of any two or more of said steps or features.

The reference to any prior art in this specification is not, and should not be taken as, an acknowledgment or any form of suggestion that that prior art forms part of the common general knowledge.

What is claimed is:

1. An apparatus comprising:
a container including a base, a first side-wall extending perpendicularly to the base, a second side-wall extending perpendicularly to the base and parallel to the first side-wall, the first side-wall and second side-wall defining an opening;
a lid in slidable engagement with the container and configured to move along a movement axis between a first configuration in which the lid covers the opening and a second configuration in which the opening is uncovered; and
a locking mechanism configured to be selectively engaged and disengaged, wherein the locking mechanism is positioned along a second axis perpendicular to the movement axis and offset from a center of the container toward a first end of the container, wherein the second axis intersects the first side-wall at a first intersection point and intersects the second side-wall at a second intersection point;

wherein the lid is configured to be maintained in the first configuration when the locking mechanism is engaged and, upon inward depression of at least one of the first side-wall at the first intersection point and the second side-wall at the second intersection point, the locking mechanism is configured to become disengaged and allow movement of the lid to the second configuration.

2. The apparatus of claim 1, wherein the locking mechanism comprises:

a first protrusion extending outwardly along the second axis from the first side-wall and a second protrusion extending outwardly along the second axis from the second side-wall; and
a first receiving portion positioned along an edge of the lid and corresponding to the first protrusion and a second

receiving portion positioned along an opposite edge of the lid and corresponding to the second protrusion.

3. The apparatus of claim 2, wherein the lid is movable from the first configuration to the second configuration when both the first protrusion and the second protrusion are disengaged respectively from the first receiving portion and the second receiving portion.

4. The apparatus of claim 1, wherein the second axis is perpendicular to both of the first side-wall and the second side-wall.

5. The apparatus of claim 1, wherein upon disengagement of the locking mechanism, the lid being movable along the movement axis in only one direction.

6. The apparatus of claim 1, wherein the container further includes end-walls arranged perpendicularly to and connecting the first side-wall and second side-wall; and

wherein each of the first side-wall and the second side-wall is longer than each of the end-walls.

7. The apparatus of claim 1, wherein the lid is configured to be placed in the first configuration by positioning the lid above the opening and pressing the lid downwardly against the container.

8. The apparatus of claim 1, wherein the container is formed of at least one of tin and aluminum and wherein the lid is formed of at least one of tin and aluminum.

9. An apparatus comprising:

a container including a base, a first side-wall extending perpendicularly to the base, a second side-wall extending perpendicularly to the base and parallel to the first side-wall, the first side-wall and second side-wall defining an opening;

a lid in slidable engagement with the container and configured to move along a movement axis between a first configuration in which the lid covers the opening and a second configuration in which the opening is uncovered;

a first protrusion extending outwardly from the first side-wall along a second axis perpendicular to the movement axis and offset from a center of the container toward a first end of the container, wherein the second axis intersects the first side-wall at a first intersection point; and

a first receiving portion positioned on an edge of the lid and corresponding to the first protrusion;

wherein the first protrusion is configured to engage with the first receiving portion to maintain the lid in the first configuration and, upon inward depression of the first side-wall at the first intersection point, the first protrusion is configured to disengage from the first receiving portion.

10. The apparatus of claim 9, further comprising:

a second protrusion extending outwardly from the second side-wall along the second axis; and

a second receiving portion positioned on an opposite edge of the lid and corresponding to the second protrusion; wherein the second protrusion is configured to engage with the second receiving portion to maintain the lid in the first configuration and, upon inward depression of the second side-wall at a second intersection point, the second protrusion is configured to disengage from the second receiving portion; and wherein the second axis intersects the second side-wall at the second intersection point.

11. The apparatus of claim 10, wherein the lid is movable from the first configuration to the second configuration when

both the first protrusion and second protrusion are disengaged respectively from the first receiving portion and the second receiving portion.

12. The apparatus of claim 9, wherein the second axis is perpendicular to both of the first side-wall and the second side-wall.

13. The apparatus of claim 9, wherein the first receiving portion is one of a slot and a recess.

14. The apparatus of claim 9, wherein the container further includes end-walls arranged perpendicularly to and connecting the first side-wall and second side-wall; and

wherein each of the first side-wall and the second side-wall is longer than each of the end-walls.

15. The apparatus of claim 9, wherein the lid is configured to be placed in the first configuration by positioning the lid above the opening and pressing the lid downwardly against the container.

16. The apparatus of claim 9, wherein the container and lid are each formed of either tin or aluminum.

17. An apparatus comprising:

a container including a base, a first side-wall extending perpendicularly to the base, a second side-wall extending perpendicularly to the base and parallel to the first side-wall, the first side-wall and second side-wall defining an opening;

a lid in slidable engagement with the container and configured to move along a movement axis between a first configuration in which the lid covers the opening and a second configuration in which the opening is uncovered;

a first protrusion extending inwardly from an edge of the lid along a second axis perpendicular to the movement axis and offset from a center of the container toward a first end of the container, wherein the second axis intersects the first side-wall at a first intersection point; and

a first receiving portion positioned on the first side-wall at the first intersection point;

wherein the first protrusion is configured to engage with the first receiving portion to maintain the lid in the first configuration and, upon inward depression of the first side-wall at the first intersection point, the first protrusion is configured to disengage from the first receiving portion.

18. The apparatus of claim 17, further comprising:

a second protrusion extending inwardly from an opposite edge of the lid along the second axis, wherein the second axis intersects the second side-wall at a second intersection point; and

a second receiving portion positioned on the second side-wall at the second intersection point;

wherein the second protrusion is configured to engage with the second receiving portion to maintain the lid in the first configuration and, upon inward depression of the second side-wall at the second intersection point, the second protrusion is configured to disengage from the second receiving portion.

19. The apparatus of claim 18, wherein the lid is movable from the first configuration to the second configuration when both the first protrusion and the second protrusion are disengaged respectively from the first receiving portion and the second receiving portion.

20. The apparatus of claim 17, wherein the lid is configured to be placed in the first configuration by positioning the lid above the opening and pressing the lid downwardly against the container.
